CLAIM

The ornamental design for a bottle, as shown and described.

DESCRIPTION

FIG. 1 is a top perspective view of a bottle, showing my new design.

FIG. 2 is a rear view thereof.

FIG. 3 is a front view thereof.

FIG. 4 is a left side view thereof.

FIG. 5 is a right side view thereof.

FIG. 6 is a top view thereof; and,

FIG. 7 is bottom view thereof.

The broken lines in the figures illustrate the portions of the bottle that form no part of the claimed design.

The dot-dash broken lines immediately adjacent to the claimed areas in the views represent the boundaries of the design and form no part thereof.
